UNITED STATES PATENT OFFICE.

ALBERT F. PRESTON, OF BOSTON, MASSACHUSETTS.

BINDING-FORMING MACHINE.

1,262,092.

Specification of Letters Patent. Patented Apr. 9, 1918.

Application filed June 4, 1915. Serial No. 32,242.

To all whom it may concern:

Be it known that I, ALBERT F. PRESTON, a citizen of the United States, and resident of Boston, county of Suffolk, State of Massachusetts, have invented an Improvement in Binding-Forming Machines, of which the following description, in connection with the accompanying drawing, is a specification, like characters on the drawing representing like parts.

This invention relates to a novel construction of a binding forming machine.

Flat or sheet patterns are employed in various arts and especially in the boot and shoe industry as forms by which different materials are cut. These patterns are superposed upon the material to be cut and a knife or other cutting instrument is passed around the edge of the pattern whereby the material is cut into the desired shape and size. The pattern edge must be protected to preserve its contour against ordinary wear incident to repeated handling and against the cutting instrument. Therefore these edges are reinforced by metal binding, U-shaped in section, which is affixed thereto by passing the pattern with the binding positioned on its edge, between clenching rollers having opposed peripheral ridges which function to press a narrow longitudinal portion of the binding into the patterns. The disadvantages arising from the use of such peripherally ridged rollers are that the convexity of binding thus applied—the line of pressure being adjacent the end of the binding—unduly thickens the bound pattern and tends to prevent it from resting evenly and flatly upon the material and that relatively deep transverse grooves are pressed in an adjoining pattern edge at corners unless the operative reduces the speed of the machine when approaching corners and stops the machine or removes the pattern therefrom precisely at the corner. These and other disadvantages well-known to those skilled in this art make it desirable to employ flat rollers which has hitherto been impracticable owing to the fact that usual binding applied to a pattern edge by such means would lack adhesive-ness and be of slight utility.

This machine provides a novel binding which may be applied to pattern edges by means of flat or substantially flat pressure rollers which apply approximately equal pressure to the whole longitudinal area of

the binding when positioned on a pattern. Retentive adherence of the binding to the pattern is assured by means of a longitudinal rib formed on the inner walls of the substantially U-shaped binding which is adapted to be pressed into the pattern surface adjacent its edge. This novel machine also rolls out and thus condenses and hardens the base of the U-shaped binding while permitting the sides to remain in a relatively flexible condition.

The object therefore of this invention is to provide a binding forming machine which produces a binding having a longitudinal inferior gripping rib or plurality of ribs.

A further object is to provide such a machine which produces a substantially U-shaped binding having a hardened base and relatively flexible sides.

Another object is to provide means on such a machine whereby the running output may be accurately measured and cut off.

Other objects of the invention will more fully appear from the following description and the accompanying drawings and will be pointed out in the annexed claims.

Figure 1 is a side elevation of the binding forming machine;

Fig. 2 is a view in elevation of the opposite side of the machine to that shown in Fig. 1;

Fig. 3 is a view in elevation of the front of the machine;

Fig. 4 is a section on the line 4—4, Fig. 1;

Fig. 5 is a section on the line 5—5, Fig. 2;

Fig. 6 is an enlarged detailed view of the front dies;

Fig. 7 is an enlarged detailed view of the rear dies.

This invention comprises means for first forming a longitudinal rib or plurality of ribs or projections upon a binding strip blank and for subsequently bending the ribbed blank into U-shaped form, the longitudinal central portion of the binding strip being automatically compacted and hardened while the metal of the edge portions is permitted to remain in its original and flexible condition. In the preferred embodiment of the invention disclosed herein the functions above described are performed by two sets of co-operating roller dies, one set being positively driven by a power mechanism herein-after to be described and the other set actuated by the passage of the binding strip therebetween as it is being drawn through

the roller dies first mentioned. Both sets of roller dies are pressed together under adjustable tension and the resistance of one set to the pull on the binding strip exerted by the 5 driven set operates to elongate the binding strip. This function overcomes the defect that the binding when affixed by rollers to pattern edges is elongated so that a pre-cut notch in the binding does not register with 10 the pattern corner for which it was cut.

This novel machine forms the complete binding through the co-operative functioning of two sets of dies, each being of the male and female roller type. These sets are 15 designated as the front and rear dies according to their mountings upon the standard. The machine comprises a standard 1 having a base 2 preferably made in a single integral casting. Both sets of dies are journaled in 20 the standard, the front dies being power-driven while the rear dies are actuatable only through the drawing of the binding therethrough by the pull exerted on the continuous binding strip by the front dies in rolling 25 the binding through them. The rear dies are geared together so as to secure simultaneity of rotation in opposite directions.

The rear female or lower die 3 is mounted upon and revoluble with shaft 4 which has 30 suitable bearings in the standard 1. This shaft extends through the standard and has secured thereto a gear 5 which meshes with a similar gear 6 secured to and rotatable with the shaft 7 which carries, rotatably 35 secured thereto at the opposite end, the rear male or upper die 8. Thus through the intermediary of the intermeshing gears 5 and 6, the upper and lower rear dies 3 and 8 positively coact to revolve at the same rate of 40 speed and in opposite directions.

The lower die 3 has a peripheral groove 9 in which the annular ridge 10 of the upper die 8 is received. The corners 11 of the groove base 12 are slightly rounded as they 45 meet the side walls of the groove while the ridge 10 of the upper die 8 has a small circumferential recess 13 on each side thereof. The base 12 of the groove is made of a width slightly narrower than the width of the 50 flat metal strip commonly used in forming such pattern bindings. The result is that, when the upper die is tensionably pressed upon a strip fed into the groove, the body of the strip will be rolled and hardened 55 while a relatively minute portion of the strip at each side will be forced into the recesses 13, pressed and formed into a hair-like flange or rib 14. While this selected embodiment shows annular flange forming recesses on each side of the face of the ridge 60 10, it is to be understood that a single recess on the one side may be employed to effect the formation of a single gripping flange. Further, an annular recess, or recesses, may 65 be made on the face of the ridge of the up-

per die as desired in order to form longitudinal ribs on the binding strip fed between the dies.

The shaft 7 is provided with a bushing 15 carried in a boring in the standard 1. The 70 boring is tapered toward the end adjacent the rear upper die 8 so that play is had for the bushing at the die end. A set screw 16 is received in threaded engagement in the standard and is adapted adjustably to impinge upon the bushing. The tension of the screw upon the bushing which forms the bearing for the shaft 7 functions to depress the rotatable shaft and thus to press the ridge 10 of the upper die more forcibly upon 80 the metal strip positioned between the dies.

The relatively large toothed-wheel 17 functions to indicate when certain predetermined lengths of binding have been formed so that the cutting means carried 85 on the front of the machine may be actuated to sever the binding as it issues therefrom. The reduced portion 18 of the shaft 7 projects beyond the upper die and has formed centrally therein a threaded aperture in which is received in threaded engagement the screw 19. The cap 20 has a projecting portion 21 which impinges against the end of the reduced portion of the shaft 7 and also offers a bearing to the indicator 90 wheel 17. The screw 19, the cap 20 and the hub 22 of the die 8 turn with the shaft 7. Yet, as the space between the cap 20 and the hub 22 of the die 8 is greater than the width of the indicator wheel, loosely mounted on 95 the bearing portion 21 of the cap, the wheel 17 is free to rotate in the opposite direction. And it is so actuated by means of a pinion 23 secured on the reduced portion 24 of the lower shaft 4. Indicating means, such as, 100 for example, an arrow A on the face of the indicator wheel, is provided whereby upon each rotation of the wheel, the cutting means may be actuated and the binding cut off into predetermined lengths. Varying length indications may be obtained by change of gear ratio between the wheel and pinion. 110

The partially formed binding, having the longitudinal ribs thereon, is drawn through the front power-driven dies. Here its body 115 portion is both turned to form outwardly flaring walls so that the binding assumes its final—a substantially U-shaped cross sectional—form and its final base portion is rolled and hardened. Power is applied by 120 means of a pulley 25 secured by means of the set screw 26 to the stud shaft 27 which has suitable bearing in the standard 1. A worm 28 is secured to and is rotatable with the stud shaft 27. The worm 28 meshes with 125 and drives in opposite directions the gears 29 and 30 revolvably secured, respectively, to the front upper shaft 31 and the front lower shaft 32. The shaft 31, similarly to the rear upper shaft 7, has a bushing 33 adjust- 130

ably positioned in a tapered boring by means of the set screw 34 similarly engaging the standard and the bushing. The front dies may, by such means, be similarly forcibly 5 pressed together.

The front male or upper die 35 is secured to and is rotatable with the shaft 31 while the front female or lower die 36 is similarly affixed to the lower shaft 32. The upper die 10 bears thereon a central peripheral ridge 37 having annular reduced portions 38. This projecting ridge 37 and its reduced portions 38 are adapted to be received within the peripherally recessed lower die 36. The annular recesses 39 on either side of the groove 40 receive the reduced ridge portions 38 of the upper die while the groove 40 receives the ridge 37. The side walls of the groove 40 and the sides of the ridge 38 are similarly 15 angularly beveled to present a passage so that, as shown in Fig. 6, when the ribbed binding is drawn through these power-driven dies the strip will be maintained in proper alinement and the ribs will not be 20 rolled or pressed. The ridge 37 of the upper die is, however, adapted forcibly to press upon the inserted binding strip, turning and forming the sides and rolling and hardening the thus formed base portion. The tension 25 of the ridge upon the binding base, as positioned in the groove, is regulated by the shaft bushing screw 34.

The completed binding as it issues from the front dies is engaged by the guide 41. 30 As shown in Fig. 1, this guide consists of a metal plate secured by the screw 42 and pins 43 to a block 44 affixed to the standard 1. The rear face of the guide corresponds to the contour of the adjacent roller 35 die and terminates in a slightly pointed portion 45. The completed substantially U-shaped binding, which has a tendency to follow the ridged roller when drawn through these dies, is engaged by the guide portion 40 45 and thereby stripped from the rollers. The guide, at its lower edge, is of a width substantially less than the base of the binding and may, therefore, be received within the binding and guide it away from the dies to the machine front. The front end 50 of this guide edge functions as the fixed member of coöperating cutting means. The block 44, which is affixed to the standard 1 by the screws 46, has pivotally mounted 55 thereon a lever arm 47. Like the guide 41, this arm is preferably made of steel. A transverse notch 48 is formed in the arm at a point whereby, upon movement of the arm, it may coöperate with the fixed guide 60 edge and cut the binding as it leaves the edge. The outer portion 49 of the arm is sufficiently long to afford a grasp for its manual actuation. In Fig. 3, the arm is shown in normal inoperative position when 65 the binding may run over the notched arm into a suitable receiver. The arm is retained in such lower inoperative position by means of a pin 50, affixed to and projecting from the block 44, which engages the top edge of the inner portion 51 of the lever 70 arm.

The operation of the machine is simple. The front and rear dies are slightly separated after releasing the tension of the screws 34 and 16. The material of which 75 this binding is preferably formed is steel in the form of narrow flat strips. Such material is sold to the trade in coils. The end of this strip is inserted directly from the coil in the rear die groove and is thence 80 fed to the front die groove. The desired tension of the male or upper dies in their respective grooves is obtained by means of the bushing set screws 34 and 16. Power 85 is then applied through the intermediary of a belt to the pulley and the front dies are simultaneously actuated. The tension of the front dies upon the metal strip not only rolls and hardens the base of the completed binding strip but also produces a friction 90 grip upon the strip and functions to draw the strip from the coil through the rear dies. As the strip is drawn through the rear dies, its two edges are upwardly turned 95 to form longitudinal flanges or ribs which process at the same time hardens these ribs. This ribbed strip then passes to the front dies where the side portions of the strip are turned preferably at an angle less than a right angle to the base or unturned portion. Through adjustment of the set screw 100 34 impinging upon the bushing of the front upper die, increased tension may be placed upon these dies and the ridge 37 may thus roll and harden the base of the completed 105 binding. The sides of the binding when turned impinge against the beveled sides of the groove 40 while the recess afforded by the beveled sides of the ridge 37 affords an unobstructed passage to the flanges or ribs 110 formed on the binding sides by the rear dies. The completed binding thus issues from the front dies, engages the guide and is presented to the path of the cutting lever arm. The gearing of the indicator wheel, 115 as disclosed, is such that the mark placed thereon completes one revolution when approximately eight feet of binding have been formed—a convenient length. When cutting the binding into such length, the 120 notched arm coöperates with the guide edge and shears off the binding.

While for sake of increased retentivity, ribs are preferably formed on each wall of the U-shaped binding, it is obvious that a 125 single rib may be formed by omitting one of the annular recesses 13 of the upper die 10 and by altering one of the corners 11 of the groove 12 so that on one side the side face of the peripheral ridge 10 will 130

run flush with the corresponding face of the groove 12 of the lower die.

This invention thus presents a novel machine for rapidly forming a ribbed, substantially U-shaped pattern binding having a hardened base and having its sides left relatively flexible. The flaring sides of this U-shaped cross sectional form greatly facilitate application of the binding to the pattern edge. The hardened base presents a more smooth and durable surface to the cutting instruments while the increased retentivity of the binding to the pattern edge afforded by the ribbed structure insures greater resistance to deterioration through rough handling and service wear.

It is to be understood that the embodiment of the invention disclosed herein is illustrative merely and not restrictive and that other forms of dies may be employed for performing the functions herein described. It is further to be understood that various forms of dies may be used to form the gripping ribs or projections and that such ribs or projections may be formed either at the margin or margins of the binding material or at such distance therefrom as may be found desirable or necessary, and that other modifications may also be made within the spirit and scope of the following claims.

Having thus described my invention, what I claim as new and desire to secure by Letters Patent is:

1. A binding forming machine comprising sets of roller dies operable to form a substantially U-shaped, flanged binding, one of

said sets comprising a peripherally ridged male die and a peripherally grooved female die, the male die having circumferential recesses on each side of the peripheral face 40 of the ridge, the female die having the corners of its groove substantially rounded to cooperate with said recesses to form a substantially filamentous flange on said binding, said corners and recesses also cooperating to prevent elongation of said filamentous flange.

2. A binding forming machine comprising a standard, means for forming a substantially U-shaped pattern binding a guide 50 positioned to be received within the formed binding and to direct the same from said forming means, and a cutting member co-operable with the end of said guide to shear the formed binding.

3. A binding forming machine comprising a standard, roller dies operable to form a substantially U-shaped pattern binding, a guide of less width than the formed binding mounted adjacent the dies, the inner end being pointed and shaped to project between the roller dies to strip the formed binding therefrom and the outer end to project beyond said dies, the outer end being shaped to form one member of a cutting means, and a cutting member co-operating therewith to shear the formed binding whereby the binding is stripped from the dies, guided therebeyond and sheared.

In testimony whereof, I have signed my name to this specification.

ALBERT F. PRESTON.
